US00D954877S

(12) **United States Design Patent** (10) Patent No.: **US D954,877 S**
(45) Date of Patent: **** Jun. 14, 2022**

(54) **GOLF CLUB HEAD**

(71) Applicant: **PARSONS XTREME GOLF, LLC**,
Scottsdale, AZ (US)

(72) Inventors: **Robert R. Parsons**, Scottsdale, AZ
(US); **Bradley D. Schweigert**, Cave
Creek, AZ (US); **Michael R. Nicolette**,
Scottsdale, AZ (US)

(73) Assignee: **PARSONS XTREME GOLF, LLC**,
Scottsdale, AZ (US)

(**) Term: **15 Years**

(21) Appl. No.: **29/754,405**

(22) Filed: **Oct. 9, 2020**

Related U.S. Application Data

(63) Continuation-in-part of application No. 29/745,977,
filed on Aug. 11, 2020, now abandoned.

(51) LOC (13) Cl. **21-02**

(52) U.S. Cl.

USPC **D21/752**

CLAIM

The ornamental design for a golf club head, as shown and described.

DESCRIPTION

FIG. 1 is a top perspective view of a golf club head;
FIG. 2 is a bottom perspective view of the golf club head;

FIG. 3 is a front elevational view of the golf club head;
FIG. 4 is a rear elevational view of the golf club head;
FIG. 5 is a top view of the golf club head;
FIG. 6 is a bottom view of the golf club head;
FIG. 7 is a left side view of the golf club head;
FIG. 8 is a right side view of the golf club head;
FIG. 9 is a top perspective view of a second embodiment of a golf club head;
FIG. 10 is a bottom perspective view of the golf club head of FIG. 9;
FIG. 11 is a front elevational view of the golf club head of FIG. 9;
FIG. 12 is a rear elevational view of the golf club head of FIG. 9;
FIG. 13 is a top view of the golf club head of FIG. 9;
FIG. 14 is a bottom view of the golf club head of FIG. 9;
FIG. 15 is a left side view of the golf club head of FIG. 9;
FIG. 16 is a right side view of the golf club head of FIG. 9;
FIG. 17 is a top perspective view of a third embodiment of a golf club head;
FIG. 18 is a bottom perspective view of the golf club head of FIG. 17;
FIG. 19 is a front elevational view of the golf club head of FIG. 17;
FIG. 20 is a rear elevational view of the golf club head of FIG. 17;
FIG. 21 is a top view of the golf club head of FIG. 17;
FIG. 22 is a bottom view of the golf club head of FIG. 17;
FIG. 23 is a left side view of the golf club head of FIG. 17; and,
FIG. 24 is a right side view of the golf club head of FIG. 17.
The broken lines shown on the drawings form no part of the claimed design.
